UNITED STATES PATENT OFFICE

2,053,143

TIMING APPARATUS

Oscar C. Frederick, Springfield, Pa., assignor to
General Electric Company, a corporation of
New York

Application July 22, 1933, Serial No. 681,700

6 Claims. (Cl. 161—1)

My invention relates to apparatus for timing industrial operations which must be repeatedly performed in a predetermined interval of time.

My invention is particularly suited for timing 5 resistance welding operations such as are encountered in spot welding or flash welding. Accurate time control of the welding current, particularly for such metals as stainless steel, aluminum and the like, is highly important. It becomes more essential with these metals than ordinary steels. It has been found that it is necessary to have the time extremely short and the current values relatively high. This is especially necessary in the welding of stainless steel, as it 15 prevents the combination of carbon and chromium which destroys the stainless qualities of the steel and permits corrosion.

It is an object of my invention to provide an improved apparatus for accurately timing a welding 20 operation independently of the operator who is free to initiate the operation but cannot thereafter interrupt it until a predetermined welding time has elapsed.

It is a further object of my invention to provide 25 apparatus of the character described which will be small in size and cheap enough to warrant its use with small sized equipments such as are used for performing certain spot welding or stud welding operations.

30 Further objects of my invention will become apparent from a consideration of the following description of one embodiment thereof which has been diagrammatically illustrated in Fig. 1 of the accompanying drawing and a modification 35 thereof shown in Fig. 2 of this drawing.

In this drawing the circuit to be controlled 1, 2 extends from a source of alternating current supply 3, 4 to the primary 5 of a welding transformer 6. This circuit is completed by an electromagnetic 40 switch 7 whose operating coil 8 is connected to the source of supply 3, 4 through the following circuit: From supply conductor 3 through conductor 9, control switch 10, which is normally biased to an open position, conductor 11, conductor 12, switch 13 of a timing relay 14, conductor 15, safety switch 16, and a conductor 17 to supply conductor 4. When the electromagnetic switch closes, an auxiliary switch 18 in shunt to the control switch 10 is also closed completing a holding 50 circuit for the electromagnetic switch through the following circuit: From supply conductor 3 through conductor 19, auxiliary switch 18, conductor 12, switch 13 of timing relay 14, conductor 15, safety switch 16 and conductor 17 to supply 55 conductor 4. The safety switch 16 may be a

hand-operated switch which is latched in the closed position until opened upon an overload through the agency of its tripping coil 20. This switch is provided to protect the control circuits which may be damaged by the flow of abnormal currents therein such as might occur upon the short circuiting of exposed conductors by a careless operator while adjusting the timing relay. 5

The movable contact of switch 13 is normally biased into engagement with the fixed contact of 10 the switch by means of an operating member 21. The end of this operating member extends between and in the path of movement of arms 22 and 23 of the timing relay 14. The arm 22 is permanently fixed to the shaft 24 of the relay and 15 the arm 23 is adjustably supported thereon and held in adjusted position relative to the arm 22 by means of a clamping nut 25. Arm 22 is provided with a dial plate 26 upon the surface of which there are graduations by means of which 20 the adjustment of the arms 22 and 23 may be facilitated. The movement of the operating member 21 is limited by adjusting screws 27 and 28 which through the agency of the operating member 21 25 constitute stops for the arms 22 and 23. The adjusting screw 28 also supports the fixed contact of the switch 13.

Forward and reverse rotation is imparted to the arms 22 and 23 of relay 14 by means of self-starting synchronous motors 29 and 30 forming part 30 of the relay. These motors may be of the construction more fully illustrated and described in United States Letters Patent No. 1,546,269, H. E. Warren, July 14, 1925. They are exactly alike, except that the shading coils 31 located in the 35 pole faces of motor 29 are arranged to cause a counterclockwise or forward rotation of the arms 22 and 23, whereas the shading coils 32 in the pole faces of the motor 30 are arranged to produce a clockwise or backward rotation of these arms. 40 The rotors of the motors 29 and 30 are mounted on a common shaft in a casing 33 which has an enlarged portion 34 enclosing a gear train by means of which the common shaft is connected to the shaft 24 upon which the arms 22 and 23 45 are supported. It is to be noted that the rotors of these motors are permanently connected to arm 22. The arrangement of rotating parts enclosed within the casing 33 and 34 may be such 50 as illustrated in United States Letters Patent No. 1,459,936, H. E. Warren, granted May 27, 1924. For timing operations of short duration the gearing is suitable to impart a complete rotation to 55 arms 22 and 23 in one second of time. The dial 55

plate 26 of arm 22 may then be marked to indicate timing periods in cycles.

Motor 29 being a synchronous motor inherently operates in step with the frequency of the source of supply 3, 4 and the arm 22 is preferably fixed on the shaft 24 so as to break the operating circuit of the electromagnet switch 7 at switch 13 at the proper time to cause the electromagnetic switch 7 to open at the zero or on the declining part of the voltage wave of the source of supply. This greatly relieves the duty on the contacts of the electromagnetic switch 7 and facilitates the operation of the control apparatus. This adjustment will, of course, depend on the characteristics of the switch used in the control circuit. I have successfully employed an electromagnetic switch having the construction disclosed and claimed in the application of Ludwig S. Walle, Serial No. 667,856, filed April 25, 1933, and assigned to the same assignee as the present application. In such a switch the contacts are sealed within a closed chamber and the arc drawn between the separating contacts generates a gas pressure within the chamber which rapidly increases and quickly extinguishes the arc. When using a switch of this description to interrupt the circuit of 10 and 25 Kva. transformers, I have found that it is necessary to open the circuit through switch 13 at approximately the peak of the voltage wave for oscillographs indicate that the operation of the pressure switch lags the operation of switch 13 by approximately a quarter of a cycle. With this adjustment the pressure switch opens the welding circuit on the declining part of the voltage wave.

The field coil 35 of motor 29 is initially connected to the source of supply 3, 4 through the following circuit: From supply conductor 3, conductor 9, control switch 10, conductors 37, 38, 39, 40, 15, safety switch 16, and conductor 17 to supply conductor 4. After the electromagnetic switch 7 has operated the field 35 of motor 29 is connected to the source of supply through the following circuit: From supply conductor 3, through conductor 19, auxiliary switch 18 of electromagnetic switch 7, conductors 11, 37, 38, 39 and 15, safety switch 16 and conductor 17 to the source of supply 4. It is to be noted that motor 30 is normally energized and is only deenergized during the operation of timing motor 29.

The field coil 36 of motor 30 is connected to the source of supply 3, 4 through the following circuit: From supply conductor 3 through conductors 9 and 40, contacts 41 of relay 42, conductors 43, 44, 39 and 15, safety switch 16 and conductor 17 to supply conductor 4. When relay 42 is energized this circuit is interrupted at contacts 41. The operating coil 45 of relay 42 is initially connected to the source of supply 3, 4 through the following circuit: From supply conductor 3 through conductor 9, control switch 10, conductors 37 and 46, safety switch 16 and conductor 17 to the supply conductor 4. After the electromagnetic switch 7 has operated the coil 45 is also connected to the source of supply 3, 4 through the following circuit: From supply conductor 3 through conductor 19, auxiliary switch 18 of the electromagnetic switch 7, conductors 11, 37, and 46, safety switch 16 and conductor 17 to supply conductor 4.

In the drawing the various parts are shown in the positions they occupy prior to the initiation of a welding operation.

The welding operation is started by closing the control switch 10. This energizes and closes the

electromagnetic switch 7 and energizes the self-starting synchronous motor 29 and simultaneously deenergizes the self-starting synchronous motor 30 through the agency of relay 42. As soon as the electromagnetic switch 7 closes the auxiliary switch 18 associated therewith is also closed. This switch is connected in shunt to the control switch 10 which is normally biased to an open position and opens as soon as the operator releases it. Once started the welding operation will continue until the arm 22 of the timing relay 14 engages the switch operating member 21 and opens switch 13 in the operating circuit of the electromagnetic switch 7. The opening of switch 13 deenergizes the electromagnet 8 of this switch as well as motor 29 and relay 42. The deenergization of relay 42 connects the motor 30 to the source of supply 3, 4 as pointed out above and this motor will then return the parts to their initial positions illustrated in the drawing. These positions will be determined by the adjustment of set screw 28 which in conjunction with the switch operating member 21 constitutes a stop for the backward movement of arm 23 which on stopping stalls the normally energized motor 30. The set screw 27 in conjunction with the operating member 21 of the switch 13 constitutes a stop for the forward movement of arm 22. The provision of such a stop is not necessary but is effective in preventing forward travel of the arms 22 after the motor 29 has been deenergized. This shortens the time required by motor 30 to reset the timing relay. Set screw 27 may in some applications of my timing relay support a fixed contact which is suitably connected in the control circuit.

It will be noted that once the welding operation has been initiated by the operator closing the control switch 10, the duration of the welding operation is no longer under his control, but is determined by the operation of the timing relay 14. However, unless the operator releases the switch 10 so that it may be returned to its normal open position, the timing relay 14 will not reset itself due to the disconnection of motor 30 from the source of supply 3, 4 at contacts 41 of relay 42 which is maintained energized so long as control switch 10 is held in its closed position.

With a timing relay of the construction illustrated in Fig. 1, it is possible for the operator to obtain a faulty timing operation if the control button 10 is closed before the resetting motor 30 has had an opportunity to fully reset the relay. This result will follow by reason of the fact that if the control button is depressed the system will be set into operation as soon as the contacts of the timing relay are closed, and these contacts will be closed as soon as the arm 22 of the relay which has opened them has been moved in a resetting direction a very short distance. By modifying the construction of the relay 14 as illustrated, in Fig. 2 of the drawing, this possibility of faulty operation of the system may be completely avoided. By referring to this figure it will be noted that the operating member 21 of the switch 13 is pivotally supported at 47 and provided with a toggle 48 by means of which it is held in engagement with the set screw 28 until arm 22 forcefully moves it therefrom and in engagement with set screw 27 until arm 23 forcefully moves it from engagement therewith. This toggle comprises a notched plunger 49 inserted in a support 50 and provided with a spring 51 inserted between the head of the plunger and the support 50. The notch in the plunger furnishes a bearing for

the pointed end 52 of the operating member 21. With a construction such as illustrated in Fig. 2 it will be noted that the operating circuit through switch 13 will not be completed until the operating member 21 for the switch has been moved to the position illustrated by a backward movement of the arm 23. It will thus not be possible for the operator to initiate an operation until the timing relay has been fully reset and, consequently, the timing operation will be of a predetermined duration irrespective of the activity of the operator.

The welding time is determined by the relative adjustment of the arms 22 and 23. Depending upon the gear reduction employed in the transmission between the arms 22 and 23 and the motors 29 and 30 the duration of the welding period may be greatly varied. In one embodiment of my invention in which the arms 22 and 23 are given one complete revolution in one second, timing operations from 2 to 50 cycles have been obtained with a 60 cycle source of supply by suitably adjusting the arms 22 and 23 relatively to one another. Oscillographic records have proved that the timing period once established may be repeated with very little error. The contacts of the switch 13 should be made of some wear-resisting material so that repeated operation of the switch 13 will not change the duration of the timing period once the apparatus has been set.

It is apparent that the switch operating member 21 may be the control element of any device which it is desired to operate after the lapse of a predetermined period of time. It is also apparent that other means than the arm 23 in conjunction with the switch operating member 21 may be used for limiting the resetting movement of arm 22. Thus, while I have described but one embodiment of my invention, it is to be understood that other embodiments thereof may be made without departing from my invention.

What I claim as new and desire to secure by Letters Patent of the United States is:

1. Apparatus comprising a movable arm, a control element located in the path of movement of said arm, a self-starting synchronous motor connected to move said arm into engagement with said control element, a second normally energized motor connected to move said arm away from said control element, means for stalling said second normally energized motor after a predetermined separation of said arm from said control element, a source of alternating current, and means for deenergizing said second motor and for connecting said first-mentioned motor to said source of alternating current until said arm operates said control element.

2. Apparatus comprising a plurality of arms, a shaft on which said arms are supported, means for adjusting the separation of said arms, timing means for rotating said shaft in one direction at a predetermined speed, resetting means operative when said timing means is inoperative for rotating said shaft in the reverse direction, a control element located between and in the path of movement of said arms, stops on each side of said control element which limit the movement thereof when actuated by said arms, means for initiating the operation of said timing means, and means operated by movement of said control element for interrupting the operation of said timing means.

3. Apparatus comprising a plurality of arms, a shaft on which said arms are supported, means

for adjusting the separation of said arms, timing means for rotating said shaft in one direction at a predetermined speed, resetting means operative when said timing means is inoperative for rotating said shaft in a reverse direction, a switch biased to either one of two positions and having an operating member located between and in the path of movement of said arms, means including said switch for initiating the operation of said timing means after said switch has been moved to one of said positions by said resetting means, and means including said switch for interrupting the operation of said timing means when said switch is moved from said one position to said other position.

4. Apparatus comprising a plurality of arms, a control element located between and in the path of movement of said arms, means for adjusting the separation of said arms, timing means for imparting a forward movement to said arms, resetting means operative when said timing means is inoperative for imparting a backward movement to said arms, means for stalling said resetting means and limiting the backward movement of said control element and said arms, means for simultaneously rendering said timing means operative and said resetting means inoperative, and means responsive to the forward movement of said control element for rendering said timing means inoperative and said resetting means operative.

5. Apparatus comprising a plurality of arms, a switch having an operating member located between and in the path of movement of said arms, the backward movement of said member being limited by said switch in its closed position, means for adjusting the separation of said arms, a self-starting synchronous motor connected to impart a forward movement to said arms, a second normally energized self-starting synchronous motor connected to impart a backward movement to said arms until one of said arms engages and is brought to rest by said operating member of said switch, a source of alternating current supply, and means including said switch in its closed position for connecting said first-mentioned motor to and for disconnecting said second motor from said source of supply until the other of said arms on its forward movement opens said switch by engaging its said operating member.

6. Apparatus comprising a plurality of arms, a switch having an operating member located between and in the path of movement of said arms, the backward movement of said member being limited by said switch in its closed position, means for adjusting the separation of said arms, a shaft on which said arms are supported, a self-starting synchronous motor connected to rotate said shaft and said arms in a forward direction, a second normally energized self-starting synchronous motor connected to rotate said shaft and said arms in a backward direction until one of said arms engages and is brought to rest by said operating member of said switch, a source of alternating current supply, a circuit to be controlled, means including an electromagnetic switch for connecting said circuit to and for disconnecting said circuit from said source of supply, a starting switch normally biased to circuit opening position, an auxiliary switch connected in shunt to said starting switch and closed and opened by the closing and opening of said electromagnetic switch, means including said starting

switch, said auxiliary switch and said first-mentioned switch for energizing and closing said electromagnetic switch until the other of said arms in its forward movement opens said first-mentioned switch by engaging its said operating member and deenergizes and opens said electro-

magnetic switch, and means including said starting switch and said auxiliary switch for connecting said first-mentioned motor to and for disconnecting said second-mentioned motor from said source of supply.

OSCAR C. FREDERICK.
